UNITED STATES PATENT OFFICE.

WALTER A. ADAMS, OF ROCHESTER, NEW YORK.

SECTIONAL TABLE.

1,425,072.

Specification of Letters Patent. Patented Aug. 8, 1922.

Application filed April 28, 1920. Serial No. 377,238.

To all whom it may concern:

Be it known that I, WALTER A. ADAMS, of Rochester, in the county of Monroe, in the State of New York, have invented new and 5 useful Improvements in Sectional Tables, of which the following, taken in connection with the accompanying drawings, is a full, clear, and exact description.

This invention relates to certain improvements in sectional tables.

More specifically the invention pertains particularly to the construction of a standard frame section adapted to be combined with similar sections arranged either laterally or longitudinally or both with respect to the first section to form a table of desired size capable of being rapidly and easily assembled and disassembled, and capable of being enlarged by the addition of similar 20 sections at any time.

A further object relates to the construction of a clamping member for securing the connecting strips or boards to respective longitudinally arranged frame sections to provide a connecting means for the sections as well as a shelf for use if desired.

Other objects and advantages relate to the details of construction of the parts of the table as will more fully appear from the following description taken in connection with the accompanying drawings in which

Figure 1 is a perspective view of a standard frame section with a clamping member used for an intermediate section assembled 35 therewith.

Figure 2 is a similar view showing a clamping member for an end section assembled with a standard frame section.

Figure 3 is a perspective view of an intermediate clamping member.

Figure 4 is a perspective view of an end clamping member.

Figure 5 is a cross section on line 5—5, Figure 4.

Figure 6 is a cross section on line 6—6, Figure 4.

Figure 7 is a cross section on line 7—7, Figure 3.

Figure 8 is a cross section on line 8—8, Figure 3.

Figure 9 is a vertical section through two standard frame sections arranged laterally end to end and secured together in the manner provided and having a suitable connecting top embodying a central partition.

As shown, the invention comprises a

standard frame section —1— mounted upon bases or pedestals —2— in an adjustable manner, as by means of bolts —3— and slots —4—, formed in the bases to permit limited 60 variation in the height of the resultant table.

The frame —1— consists of vertical uprights —5— and —6—, and upper and lower cross walls —7— and —8— respectively. The cross walls may, as shown, be formed 65 with flanges —9— and —10— respectively, some of which may be formed with open-sided slots for the reception of screws or other attaching means in the connecting bars —11— or the top parts —12—. 70

Preferably the frame parts are T-shaped in cross section throughout with the base of the T extending downwardly from the cross walls —7— and —8— and inwardly from the vertical uprights or posts —5— and 75 —6—.

One post, as —5—, may be formed with an enlargement —13— forming the reinforced part permitting the formation of a bolt opening —14— through which the bolt 80 —15— may extend when two of the frame parts are arranged laterally end to end.

When so arranged, as shown in Figure 9, the top plates or boards —12— are formed with flanges —16— adapted to be seated in 85 grooves in the opposite side of a central partition —17— which partition is thus supported in operative position when the top plates are secured to the frame sections. The cross wall —8— may be formed with a 90 series of enlargements —18— constituting reinforced parts permitting the formation of vertical bolt openings for the purpose of securing clamping bars —19— in proper position relatively to the frame section to grip 95 the oppositely extending connecting members or boards —11—.

A minimum of two frame sections is required, spaced by a suitable top —12— and suitable connecting boards —11— for the 100 formation of a complete table. Any number of sections and essential parts may thereafter be added to form a table of the desired length, and by duplication of this arrangement a table of double width may be 105 formed. The connecting members or boards —11— are of a suitable length so as to extend between the frame sections —1— and terminate at substantially the central portion of the respective cross-bars or walls 110 —8— and where the table is to be formed of three sections longitudinally arranged,

the intermediate section is provided with the clamping member shown in Figure 3, while each end section is provided with a clamping member as shown in Figure 4.

- 5 The clamping member of Figure 3 comprises an elongated substantially flat strip —20— having each of its ends formed in a yoke —21—, each yoke adapted to receive one of the vertical uprights —5— or —6— 10 respectively so that the clamping member may slide vertically along the uprights and for this purpose the yoke parts are widened vertically so as to extend above the flat plate-like portion —20—.
- 15 Extending from the opposite side of the strip —20— is a series of box-like structures —22— formed by connected flanges projecting downwardly from the side plate and spaced apart a sufficient distance to receive between them the connecting bars —11—.

20 The plate —20— is further provided with downwardly projecting flanges extending between and connecting the box-like structures —22—, the two flanges adjacent the ends of the flattened strip —20— terminating at the base of the opening in the yokes —21—.

It will be understood from the drawings and this description that the ends of the 30 connecting bars —11— rest upon the cross walls —8— and that the ends of the connecting bars abut against the flanges —23—.

35 Bolts 50 are then passed through the openings in the reinforced parts —18— through the box-like structures —22— and openings —24— in the plate —20— and by the use of suitable nuts the parts are drawn tightly together to grip the connecting bars —11— and hold them rigidly in position. In order to effect this more positively, particularly in connection with connecting bars of slightly varying thickness, the plate —20— is provided with V-shaped tangs —25— intermediate the box-like portions which are 40 adapted to be pressed into the connecting bars to make the engagement more rigid and permanent.

45 It will be noted that the end-clamping members —26— should be formed to receive connecting bars —11— only upon one side of the flanges —23— and for the purpose of covering the ends of the connecting bars and portions of the cross-walls —8— the end-clamping bar —26— is formed with a laterally extending part —27— forming a continuation of the plate —20— and provided with a pair of longitudinally extending flanges substantially parallel with the flanges —23— and extending below the flanges —23—, the 55 inner flanges —28— resting upon the pro-

jections —10— and reinforcing the box-like structures —22— and the outer flanges —29— forming an end-covering for the parts.

60 The flanges —10— may form receiving means for screws —30— adapted to engage the connecting bars —11— to assist in forming a rigid structure.

65 Although I have shown and described a specific form and construction of device and parts thereof, I do not desire to limit myself to the same as many and various changes and modifications in the details of form and construction may be made without departing from the spirit of this invention as set forth in the appended claims.

70 What I claim is:

1. The combination with a frame comprising spaced uprights and connecting cross bars of a clamping member having its opposite ends bifurcated and slidably mounted on respective uprights and its intermediate portion formed with a series of depending boxlike structures spaced by depending longitudinally extending flanges and means for 80 securing the clamping member to one of the cross bars.

2. The combination with a frame comprising spaced uprights and cross bars extending between the uprights of a clamping member having its opposite ends slidably mounted on respective uprights and its intermediate portion formed with a series of depending spaced boxlike structures and means for securing the clamping member to 90 one of the cross bars.

3. The combination with a frame comprising spaced uprights and a cross bar connecting the uprights of a clamping member adapted to engage the cross bar and formed 100 with a series of depending latitudinally extending flanges and longitudinally extending flanges connecting the said latitudinally extending flanges.

4. In a knock-down table a rigid rectangular frame comprising a pair of uprights and connecting cross bars, a clamping member having its opposite ends bifurcated for slidably engagement with said uprights respectively, and its intermediate portion formed 110 with a series of projecting box-like structures in substantial contact with one of said cross-bars, and means for securing the clamping member to the cross bar.

115 In witness whereof I have hereunto set my hand this 6th day of March, 1920.

WALTER A. ADAMS.

Witnesses:

HOWARD P. DENISON,
H. E. CHASE.
